UNITED STATES PATENT OFFICE.

SIMON B. HESS, OF NEW YORK, N. Y.

BURGLAR-ALARM SYSTEM.

1,298,710.

Specification of Letters Patent. Patented Apr. 1 1919.

Application filed May 17, 1915. Serial No. 28,792.

To all whom it may concern:

Be it known that I, SIMON B. HESS, a citizen of the United States, residing in New York city, in the county of New York and State of New York, have invented certain new and useful Improvements in Burglar Alarm Systems, of which the following is a specification:

This invention relates to improved electric 10 burglar alarm systems and aims to provide a system in which a greater degree of protection is obtained by the use of a plurality of normally closed protective circuits, such additional protection being due to the fact 15 that upon the accidental breaking of any one of said closed protective circuits there will be given an alarm showing that that circuit is inoperative, in which latter case the others of said closed protective circuits 20 will still be operative to actuate an alarm upon interference with the protected structure.

The invention consists, in detail, of a source of current supply, twin protective 25 circuits supplied continuously thereby, each of said protective circuits containing a visible alarm, preferably a lamp, which is, therefore, continually burning when its circuit is intact, and each protective circuit 30 containing one coil of a pair of electro-magnets having the same magnetic circuit. These electro-magnets are arranged normally to hold an armature out of engagement with a contact in another circuit; this second 35 circuit containing an audible signal as a bell. The strength of the above mentioned electro-magnets is so calculated that either one produces enough magnetic flux to hold attracted the armature but not enough to attract it from its withdrawn position against 40 the contact in the secondary circuit. This arrangement permits the giving of a visible signal when either protective circuit is broken but prevents the giving of an audible signal unless both circuits are broken.

There is also provided a novel arrangement comprising a pair of electro-magnets having separate circuits and an armature common to both, one of the windings of the said elec-

tro-magnets being included in the above 50 mentioned secondary circuit while the other is included in another circuit containing a source of current supply and a switch. By the use of suitable contacts on the armature the audible signal secondary circuit is completed when both protective wires are broken 55 and immediately thereafter the secondary circuit is broken again thus preventing needless waste of current. By the manipulation of a compound switch, the entire system may 60 be conveniently reset.

There is also provided in this invention certain novel means whereby the source of supply for the closed protective circuits may be the public service mains, thus eliminating 65 the cost and annoyance incident to the use of batteries.

Referring now to the drawings:—

Figure 1 is a diagrammatic view showing the protective system installed in the show- 70 window and door of a store.

Fig. 2 shows a type of molding intended to be used in installing the two wire protective system.

Fig. 3 is a view of the ordinary molding 75 used in installing a one wire system, and

Fig. 4 is an enlarged view of certain hereinafter described relay contact parts.

Fig. 5 is a diagrammatic view showing the method of connecting the protective cir- 80 cuits to the public service mains.

Fig. 6 shows another method of connecting thereto.

Fig. 7 shows still another method of connecting thereto. 85

In Fig. 1 there is shown at 10, a resistance having contact clips 11, 12 and 13 thereon. Current is caused to flow through said resistance 10 by means of connection of its terminals T—T' to the service mains S and 90 owing to this current flow, differences of potential are caused to exist between the clips 11, 12 and 13, thus causing current to flow in the circuits connected thereto. Such current may be considered to flow from the clip 95 11, through the wire *a* to the bell box 15, through the inner lining thereof 14 (this bell box being similar to that described in my

Patent No. 901,171, issued October 13, 1908,) passing thence by the wire *b* to the incandescent lamp 16 (keeping it alight), thence by wire *c* along the edges of the glass windows X and Y and to the contact 17 on the door Z, thence through the wire *d* in the molding on the door Z to contact 18, thence by wire *e* to switch arm 19. (The compound switch 20 of which arm 19 is a part is here 10 shown thrown to the left thus completing all protective circuits). From said switch arm 19 the current continues through the wire *f* to the winding 21 of the electro-magnetic relay 22 and thence by the common return wire 15 *g* to the clip 12 thus completing one protective circuit.

Similarly the current may be considered to flow (although strictly speaking the flow is in reverse direction to the direction in 20 which we shall now trace it) from the clip 13 through the wire *a'*, through the outer casing 14' of the bell box 15, thence through the wire *b'*, the lamp 16' (keeping it alight), thence by wire *c'* along the edge of the window X, the window Y to the contact 17' on the door Z; through wire *d'* in the molding on the door Z to the contact 18', thence by wire *e'* to the winding 21' of the relay 22, thence by the common return wire *g* to clip 30 12, thus completing the other protective circuit.

The current in the winding 21 and the current in the winding 21' are arranged to produce in their common magnetic circuit cumulative fluxes, thus causing the armature 23 to be attracted to and held against the pole pieces 24. This state of affairs will exist as long as current passes in, at least, one winding of the pair 21, 21', in other words so 40 long as, at least, one of the protective circuits is intact, for in the event of the failure of one of such circuits current will be cut off from one winding of the relay 22, which cutting off of current will not cause the armature 23 to fall owing to the fact that the normal flux produced by one of the windings of said relay 22 is sufficient to hold said armature 23 against pole pieces 24, 24. On the cessation of current in either of the protective circuits, its corresponding lamp 16 or 16' will be extinguished thus giving notice of that fact. These lamps 16, 16' are preferably mounted in the store-window so as to be plainly visible from the street.

Now considering the secondary circuit mentioned in the foregoing condensed description, the armature 23 forms together with the contact stop 25 part of the circuit. This circuit may be most conveniently traced 60 from the battery 26 through the wire *h* to the armature 27 of the relay 28. The normal position of said armature 27 is to the left against the contact stop 29; thus normally the circuit may be traced from the armature

27 to the stop 29, through the wire *i*, through 65 the electro-magnet winding 30, the wire *j* to the stop 25, the armature 23, the switch arm 31 of the compound switch 20, thence by the wire *k* to the battery 26 completing the secondary circuit.

Now when both protective circuits are interrupted as by the attempted entry of an unauthorized person, both windings 21, 21' of the relay 22 are deenergized, causing the pole pieces 24, 24 to release the armature 23 70 and allowing it to close the contact between said armature and the contact point 25. Such closure allows current from the battery 26 to flow momentarily in the secondary circuit of which electro-magnet 30 is a part 75 thus causing said magnet to attract the armature 27 against the contact stops 32 and 33 thereby breaking the connection of armature 27 to stop 29 thus cutting off current from the magnet 30. (It should be here 80 stated that armature 27 is not biased in either direction but remains wherever thrown). Current is then allowed to flow from the battery 26, through wire *h* to armature 27, stop 32, wire *l* to the bell 34, thence 90 by way of the wire *m* back to battery 26 thus causing bell 34 to ring giving an audible alarm.

In order now to reset the system all that is necessary is to repair the breaks in the 95 protective circuits whereupon the manual throwing to the right of the compound switch 20 resets the relay 28. When switch 20 is in this right hand position current flows momentarily from battery 26 through wire 100 *h*, armature 27, stop 33, winding of magnet 35, wire *n*, switch arm 36, wire *o*, to switch arm 31, and along wire *k* back to battery 26 and energizing the magnet 35 causes it to pull armature 27 into its normal left hand 105 position. Now returning to its normal left hand position the compound switch 20, the circuits feeding the windings 21, 21' being intact the coils of relay 22 attract their armature 23 and all circuits are as before interference and ready to give alarm again.

In Fig. 2 there is shown a section of wire molding consisting of a wood strip 37 having on one side two longitudinal slots 38 into which may be conveniently placed the protecting wires as for instance the wires *d*, *d'* in Fig. 1.

In Fig. 3 is shown the ordinary one wire molding in common use consisting of a half round strip 39 having a slot 40 in its round- 115 ed surface.

In Fig. 4 the preferable form for the contact stops 29, 32, 33 is shown. These consist each of a flat strip 41 having a spring strip 42 screwed thereto and forming a spring 120 fork to receive the armature contact 27.

In Fig. 5 there is shown a method of connection of the protective circuits to the pub-

lic service mains which is similar to that shown in Fig. 1 but has in addition, an electro-magnetic breaking device intended to break the circuit containing the resistance 5 whenever a disturbance of the current in the protective circuits occurs. This effect is accomplished by the use of a doubly wound relay having its windings arranged to oppose one another. In the figure S indicates the 10 service mains which are shown as of the three-wire standard type. From the main S two taps, 43 and 44 are taken (44 from the neutral main and 43 from either outside main), the tap 43 leading to a pair of circuits in shunt, one of said circuits containing 15 the resistance R, the relay coil C, the wire 45 and the tap wire 44, and the other containing the resistance R', the contact stop 46 (normally engaging the armature 47), the 20 armature 47, the relay coil C', the wire 48, the rheostat resistance 10 and the tap wire 44. With this arrangement of circuits, in 25 the event of a disturbance of the balance of current in the two above described circuits, if such disturbance consists of a predominance of current in coil C over that in coil C', or vice versa, armature 47 will be withdrawn from stop 46, thus breaking the 30 circuit containing the rheostat 10, thereby cutting off current from both protective wires a and a' and causing the alarm apparatus to operate as hereinbefore described.

In Fig. 6 there is shown another system similar to that shown in Fig. 5 but in this 35 arrangement the terminals of the resistance 10 are (through various other apparatus) connected to the two outside wires of the service mains and also the clip 12 (Fig. 1) is dispensed with; the wire g being here 40 grounded and thus effectively connected to the neutral wire of the three wire mains. There is, in addition, provided a tell-tale lamp 52 showing when current is being supplied to the resistance 10 and furthermore 45 there is provided an audible alarm circuit 53 giving alarm when armature 47 is displaced and also a lock 54 to hold said armature in its displaced position. The operation of this arrangement is similar to that of 50 the arrangement shown in Fig. 5.

In Fig. 7 is shown an arrangement similar to that in Fig. 5, but with the insertion of an extra pair of contacts 49, 50 in the wire 44; 55 51 being a contact plate mounted on the armature 47 and 49 and 50 being stop contacts intended to coöperate therewith. This arrangement has the effect that upon a disturbance of current in either of the coils C and C' vibration of the armature takes place 60 and consequently flickering of the signal lamps 16, 16'.

It will obviously be evident to one skilled in the art that various changes may be made in the scheme of wiring herein disclosed, as

well as in the arrangement of the switches, 65 without departing from the spirit of the invention.

The method of connection to the public service mains herein shown is not herein claimed, but is claimed in my copending application, filed July 30, 1917, Serial No. 183482.

I claim:

1. In an alarm system, the combination with public service electric mains, of a resistance connected between two of said mains, alarm circuits connected to said resistance, visible signaling means in said alarm circuits normally operative to indicate that the alarm circuits are intact, each visible signaling means being rendered inoperative when its alarm circuit is tampered with, and audible signaling means adapted to be energized when said alarm circuits are deenergized.

2. In an alarm system, the combination with public service electric mains, of a resistance connected between two of said mains, two alarm circuits connected to said resistance, separate visible signaling means in each alarm circuit, each normally operative to indicate that its alarm circuit is intact, each visible signaling means being rendered inoperative when its alarm circuit is tampered with, and audible signaling means adapted to be energized when both said alarm circuits are deenergized.

3. In a burglar alarm, the combination with a guarded structure of a visible signaling means and an audible signaling means, said visible signaling means comprising two signals, of two protective circuits each connecting the guarded structure with one of said signals, both of said protective circuits being connected with said audible signaling means, said visible signals being normally operative to indicate that the apparatus is in order and that the guarded structure has not been tampered with, either of said signals being rendered inoperative when its protective circuit is disturbed, said audible signaling means being energized only when both of said protective circuits are disturbed.

4. In an alarm system, the combination with a visible signaling means and an audible signaling means, of a source of current for the visible signaling means, two alarm circuits connecting said visible signaling means with said source of current, an electromagnet having two windings, one operatively connected in each circuit, an armature attracted by said magnet when said windings are energized, a second armature, a second source of current connected with said first and second armatures and with said audible signaling means, a first contact connected with said audible signaling means

and coöperating with said second armature to energize said audible signaling means, a second contact coöperating with said first named armature, a third contact coöperating with said second armature and connected with said second contact, a second electromagnet associated with said second armature and connected in series with said second and third contacts, whereby when said first named armature is retracted said second electromagnet will be energized and attract said second armature so that it will open the circuit of said second electromagnet and connect with said first contact to energize said audible signaling means.

5. In an alarm system, the combination with two alarm circuits of two visible signaling means, each associated with a separate one of said alarm circuits, each of said 20 visible signaling means being normally operative to indicate that the associated alarm circuit is intact and being rendered inoperative when said alarm circuit is deenergized.

6. In an alarm system, the combination 25 with two alarm circuits of two visible signaling means, each associated with a separate one of said alarm circuits, and an audible signaling means, each of said visible signaling means being normally operative to indicate that the associated alarm circuit is intact and being rendered inoperative when said alarm circuit is deenergized; and said audible signaling means being energized when both alarm circuits are deenergized.

30 7. In an alarm system, the combination with an audible signaling means, of an armature, a source of current connected with said armature and with said audible signaling means, a first contact connected with 40 said audible signaling means and associated with said armature, said audible signaling means being normally deenergized, an alarm circuit controlling said armature and adapted to actuate said armature to coöperate with 45 said first contact to energize said audible signaling means whenever said alarm circuit is deenergized, and means for resetting said armature, said resetting means comprising a second contact associated with said armature, an electromagnet associated with said 50 armature, and a switch; said second contact, said switch, and said electromagnet being connected in series, whereby when said switch is closed said electromagnet will be 55 energized and attract said armature so that it will open the circuit of said audible signaling means.

8. In an alarm system, the combination with public service electric mains, of a resistance connected between two of said mains, alarm circuits connected to intermediate points in said resistance, visible signaling means in said alarm circuits normally operative to indicate that the alarm

circuits are intact, each visible signaling 65 means being rendered inoperative when its alarm circuit is tampered with, and audible signaling means adapted to be energized when said alarm circuits are deenergized.

9. In an alarm system, the combination 70 with public service electric mains, of a resistance connected between two of said mains, two alarm circuits connected to intermediate points in said resistance, separate visible signaling means in each alarm 75 circuit, each normally operative to indicate that its alarm circuit is intact, each visible signaling means being rendered inoperative when its alarm circuit is tampered with, and audible signaling means adapted to be energized 80 when both said alarm circuits are deenergized.

10. In an alarm system, the combination with an alarm signaling means, an alarm circuit controlling said means and adapted 85 to trip said means to cause a continuous alarm whenever said alarm circuit is deenergized, and means for resetting said alarm signaling means, said resetting means comprising an armature associated with 90 said alarm signaling means, an electromagnet therefor, a switch, and a circuit for said electromagnet controlled by said armature and said switch.

11. In an alarm system, the combination 95 with an alarm signaling means, an alarm circuit controlling said means and adapted to trip said means to cause a continuous alarm, and means for resetting said alarm signaling means, said resetting means comprising an armature associated with said 100 alarm signaling means, an electromagnet therefor, a switch, and a circuit for said electromagnet controlled by said armature and said switch.

12. In an alarm system, the combination with two alarm circuits of an alarm signaling means, said alarm signaling means being energized only when both alarm circuits are tampered with.

13. In an electric system, a signaling means, an electromagnet controlling a first contact in circuit with said means, a second contact in circuit with said electromagnet controlled by said electromagnet, and a second electromagnet also controlling said first contact.

14. In an electric system, a signaling means, an electromagnet controlling a first contact in circuit with said means, a second contact in circuit with said electromagnet controlled by said electromagnet, and a second electromagnet also controlling said first contact and said second contact.

15. In an alarm system, an electric signaling means, first and second electromagnets, a first switch for said electric signaling means, a second switch for said first electro-

magnet, and a third switch for said second electromagnet, said first electromagnet being adapted to open said second switch and close said first and third switches, and said second electromagnet being adapted to close said second switch and open said first and third switches.

16. In an alarm system, an electric signaling means, a first electromagnet for closing the circuit of said electric signaling

means, and a second electromagnet for opening the circuit of said signaling means, each electromagnet being adapted to close the circuit of the other electromagnet and to open its own circuit.

15

Signed at New York in the county of New York and State of New York this 11th day of May, A. D. 1915.

SIMON B. HESS.
